PUMP SPRAY

Stanley A. Hayes, Pasadena, Calif.

Application September 24, 1945, Serial No. 618,285

15 Claims. (Cl. 222—375)

1

This invention deals with hand-operated pump sprays, spray guns and the like in which a spray-head or other discharge device tends to drain liquid from a container through a pump if it is left at a level below that of the liquid in the container and siphoning is permitted to occur. The invention provides a simple but reliable structure which automatically prevents such siphoning action, and in its preferred form, also provides automatic means for agitating the contents of the container.

A common type of hand spray useful for spreading insecticides, detergents and the like in liquid solution or suspension comprises a container, such as a glass fruit jar, a piston type pump with a hand-operated plunger mounted on the top of the container and projecting downwardly into it, and an outlet line such as a flexible hose or tube fastened to the pump at its inlet end and having a spray-head or nozzle on its discharge end. Such devices are simple to construct and operate, and have a wide field of usefulness. However, many such devices are so constructed that the contents of the container will siphon through the pump and out the outlet line or conduit if the discharge end is left at a level below that of the liquid in the container. This is annoying and may be dangerous when the liquid is of toxic or corrosive character.

I have developed a spray apparatus of the general type described but provided with a combination of structural elements which cooperate to prevent siphoning, and which in its preferred modification is provided with means for automatically agitating during the pumping operation the liquid to be pumped. This latter feature is particularly useful when dealing with slurries or suspensions of finely divided solids in water—for example such widely applied plant sprays as "lime-sulphur" or Bordeaux mixture. Moreover, my preferred structure is rugged, inexpensive to construct, and requires less force for operation than guns or sprays of this general type heretofore available.

In essence, my invention contemplates apparatus of the type described having a container for liquid, and a pump mounted on the container with a cylinder projecting downwardly into the container. A tubular plunger is mounted in the cylinder. Its upper end projects outside the container and is connected to a discharge conduit, preferably a flexible tube, which may have a spray-head or the like on its free end. There is a vent to atmosphere in an upper portion of the wall of the cylinder, and springing means, pref-

2

erably mounted within the cylinder, are provided for holding the lower end of the plunger at a level above the vent in the cylinder wall except when exterior pressure is exerted to force the plunger down and thus operate the pump. Should the discharge end of the conduit be left below the level of liquid in the container no siphoning can occur because the lower end of the plunger will draw air from the vent and "break the siphon."

These and other features of the invention are made plain in the following detailed description and the accompanying single figure which is a fragmentary elevation, partly in section, of a preferred type of spray gun.

The apparatus illustrated comprises a container, for example an ordinary glass fruit jar 10 having a neck with an outside thread to which a pump assembly is screwed.

The pump assembly has an upright cylinder 11 of circular cross-section which extends concentrically of the jar from a point above its mouth to a point within a short distance of its bottom.

An annular foot valve seat 12 is sweated on the lower end of the cylinder and is provided with an interior raised tubular portion having a flat annular upper face upon which a valve disk 13 sits when the apparatus is at rest. An annular cage or keeper 14 is disposed within the cylinder above the valve seat, and has an inside diameter such that the valve disk is free to rise in the cage under the influence of a current of liquid passing upward through the seat. The upper face of the keeper is perforated to permit the passage of water from the jar to the pump cylinder.

A retainer sleeve 15 having an inner flange 15A on its upper end is slidably fitted within the cylinder and rests on the cage or keeper of the foot valve. A frusto-conical helical spring 17 rests its larger end on the flange and extends upward to bear against the under side of a plunger assembly 18. The lower end of the spring is only slightly smaller in diameter than the inside of the cylinder, whereas the upper end is smaller so as to hug the plunger assembly. When the plunger assembly is pushed down, the successive coils of the spring tend to collapse within each other, thus offering minimum resistance to compression and thrust against the cylinder wall, with the result that the pumping is accomplished with less force than would be the case if the spring hugged the wall of the cylinder for a substantial distance.

The piston assembly comprises a concentrical-

ly disposed tubular stem 19 with a threaded lower end bearing an upper nut 20 (which bears against a light upper shoulder 21 on the stem, so that its position is easily fixed in assembly) followed successively by an upper washer 22, a single pump leather 23 (with its edge turned down against the cylinder wall), a lower washer 24, and a head valve cage 25, threaded on the lower end of the stem.

The head valve cage has an inner chamber with a hemispherical seat upon which rests a ball 26, preferably of resilient material such as semi-hard natural or synthetic rubber (preferably "neoprene") thus closing a bore 27 in the bottom of the seat. Vertical grooves (not shown) are cut on the end of the stem over which the cage is screwed to permit the passage of liquid around the ball when the latter leaves the seat and rises against the end of the tube.

The mouth of the jar is closed by a cap assembly comprising a cap 28, a lower handle 29, and a bushing 30. The cap is spun in approximately frusto-conical shape with a lower thread which screws over the jar mouth and a smaller upper thread within which a rolled thread on the upper end of the cylinder is screwed. The thread of the cylinder extends above the cap and is screwed into a thread rolled into the lower portion of the handle 29. This latter member is an approximately boat-shaped member having ends projecting horizontally on opposite sides of the center line of the apparatus. The handle 29 is screwed down on the top of the cap, so as to lock it to the threads on the cylinder. The bushing, like the cap, is spun out of sheet metal and has a concentric lower tubular portion 30A in which the stem of the plunger fits slidably, an intermediate section 30C having rolled threads screwed into the top of the cylinder and a still larger upper portion 30B provided with wings 30D or the like to facilitate assembly, but which do not project above the boat-like cavity within the lower handle.

The stem of the piston projects through the bushing to a point well above the lower handle where it is threaded into the lower end of an outlet tube 31 that is bent at right angles and cast within a solid upper handle 32 of plastic or the like and shaped like the outside of an inverted boat with two ends extending horizontally in the plane of the lower handle. The other end of the outlet tube extends through one end of the upper handle and is threaded internally to receive a bushing 33 over the outer and smaller end of which is fastened a small diameter flexible tube 34 of rubber, or the like. Fastening of tube to bushing is accomplished by exterior threads on the bushing over which the tube is twisted, there being a coil 35 of spring wire of hand opposite to the thread on the bushing screwed over the joint to give additional security.

The flexible tube may be of any convenient length, say 2 or 3 feet, and carries a spray assembly 36 on its free end. The spray assembly comprises a pipe 37 to which the flexible tube is fastened by thread and exterior spring coil as in the case of its opposite end just described. A plastic handle of any convenient shape is cast around the end of the pipe adjacent the connection for the flexible tube. The other end of the pipe carries a spray-head 38 in the form of a cylinder bored internally threaded at one end to receive the pipe, which is seated against a washer 39. A smaller bore 40 extends from the washer seat into a cut-out portion having a

slanting front face 42 which serves to deflect a stream of liquid ejected from the pipe and spread it as a fan-shaped spray.

The spring within the pump cylinder is of such strength and length that it always forces the upper nut of the plunger assembly up against the lower end of the bushing through which the stem extends, i. e. to the extreme upward position of the plunger assembly. Preferably the spring is under slight compression even when the plunger is in such position, thus giving a greater degree of positiveness to the action of the device.

An inside vent or breather hole 43 of relatively small diameter is provided in the wall of the pump cylinder a short distance below the bottom of the plunger assembly, i. e. the bottom of the cage 25, considering the assembly to be in its extreme upper position with the upper nut in contact with the bushing. An outside vent or breather hole 44 is provided in the cap. This vent also is of small diameter and preferably is placed out of line of the interior vent, so that liquid squirted through the interior vent will not have a straight-line path to the outside.

The length of stem projecting above the lower handle and the length of the spring in the cylinder are proportioned to provide a plunger stroke of approximately 2 to 3 inches, so that an operator may grasp both upper and lower handles and squeeze them together easily.

Assuming that a suitable quantity of liquid is present in the apparatus, the squeezing together of the handles will push the plunger down the cylinder against the spring. The foot valve in the bottom of the cylinder will check the flow of liquid downward out of the cylinder and the ball in the head or check valve on the end of the stem will rise to permit flow of a column of liquid into the stem and thence to and out of the spray-head through the outlet tube, the flexible tube and the pipe. As the hand of the operator is relaxed the upper and lower handles spring apart, the ball in the check valve of the plunger assembly seats to prevent liquid from flowing back through the stem, and the disk on the foot valve rises to permit more liquid from the jar to enter the pump cylinder.

The foregoing cycle is repeated each time the handles are squeezed together and released; and each time a jet of liquid is squirted out of the spray-head.

If the spray gun is left with liquid in the jar and with the spray-head hanging down below the level of this liquid, there will be no siphoning effect, such as occurred with prior types, and so spills are effectively avoided. The inside and outside breather holes are above the normal level of liquid in the jar, and are in fact above the top of the jar. Liquid entrapped in the series of conduits above the head or check valve of the plunger can not, in running toward the spray head, pull more liquid through the check valve, for the lower end of the latter is surrounded by air at atmospheric pressure.

The two breather holes or vents should be large enough to avoid clogging but small enough that pumping efficiency is not impaired seriously. For a quart fruit jar spray, holes 1/8 inch in diameter are a fair compromise.

The inside vent could be connected direct to the atmosphere by a tube or the like passing from the cylinder wall through the cap. This would permit effective breaking of the siphon, but is undesirable in that squirting would occur, since a small amount of liquid is forced through the

vent as the spring pushes the plunger up from its lower position. In the apparatus described, the liquid thus ejected is simply by-passed back into the jar, for the outside vent is out of the line in which the liquid is propelled from the inside vent.

When suspensions of solids in liquid are placed in the jar, there is a tendency for the solids to settle to the bottom, especially upon standing, so that a restricted amount of agitation of the liquid in the jar is desirable. This is accomplished in the apparatus described by means of a small agitator hole 45 in the disk of the foot valve. As the plunger is lowered, the foot valve closes, but a small jet of liquid is forced down through the hole to provide agitation in the jar, especially in the neighborhood of the foot valve, thus inhibiting clogging in that zone and generally agitating the contents of the jar. As in the case of the breather holes, the hole or by-pass in the disk should be large enough to project an adequate volume but not so large that pumping efficiency is seriously impaired. In a quart fruit jar sprayer a hole $\frac{1}{32}$ " in diameter or even smaller has proved adequate.

The agitator hole could be placed in the wall of the pump cylinder proper or in the valve seat. However, it is preferable to place it in the disk itself and to make the disk of flexible material, since in this way the flexing of the disk and its flutter up and down tend to keep solid particles from clogging the agitator hole.

The foot valve need not be placed at the bottom of the jar. It could, for example, be placed at the level of the flange on the retainer sleeve, but in such case the effect of the jet through the agitator hole in the valve disk would be largely damped; and agitation at the bottom of the jar would be much diminished. The structure illustrated is, therefore, to be preferred over the modification suggested, although both are within the scope of the invention.

If desired, the spring, instead of being mounted in the cylinder below the plunger, can be placed around the stem between the upper and lower handles, and various other modifications can be made, such as the use of a tension-type coil spring in the cylinder between bushing and plunger proper or a compression-type leaf spring between the handles, the essential being that the spring hold the suction end of the plunger assembly above the breather.

The spray gun illustrated in the drawing has been designed with a view toward operation with pressure that can be exerted easily by the average hand. To this end a simple deflector type fan-spray head is employed, since this gives a relatively fine spray with minimum effort. To the same purpose the spring in the cylinder is designed to avoid wall friction and only a single plunger leather is provided. It will be understood, however, that other types of spray-heads, springs and plunger leathers may be employed in the practice of the invention.

The spray gun illustrated is particularly useful for wetting surfaces with "DDT" solutions and the like. Such insecticide solutions should be applied as a spray, as distinguished from a mist, since the lethal effect upon insects is furthered by applying the solution as a film to wall surfaces and the like so as to furnish maximum contact, whereas a mist which hangs in the air does little damage to insects, but is injurious if breathed by higher forms of life.

I claim:

1. In apparatus of the class described, the combination which comprises a container for liquid, a pump having a cylinder projecting downwardly into the container, and a tubular plunger in the cylinder having an inlet from the cylinder, an exterior conduit connected to the tubular plunger having a discharge end which may be disposed below the level of liquid in the container, a valve in the tubular piston above the inlet and so constructed that it opens when the plunger is lowered but otherwise remains closed, a vent to atmosphere from a point in the upper portion of the cylinder chamber, and spring means for holding the inlet above the vent point.
2. In apparatus of the class described, the combination which comprises a container for liquid, a pump having a cylinder projecting downwardly into the container, and a tubular plunger in the cylinder having an inlet from the cylinder, an exterior conduit connected to the tubular plunger having a discharge end which may be disposed below the level of liquid in the container, a valve in the tubular piston above the inlet and so constructed that it opens when the plunger is lowered but otherwise remains closed, a vent to atmosphere through an upper portion of the wall of the container, a second vent connecting an upper portion of the container with an upper portion of the cylinder interior, and spring means for holding the inlet above the vent point when exterior pressure on the plunger is relaxed.
3. Apparatus in accordance with claim 1 in which the valve comprises a cage with a seat and a ball disposed in the seat but free to move upwardly within the cage.
4. Apparatus according to claim 1 in which the vent to atmosphere comprises an orifice through an upper portion of the wall of the container and a second orifice through an upper portion of the wall of the pump cylinder.
5. Apparatus according to claim 1 provided with a foot valve disposed in a lower portion of the pump cylinder and connecting the latter with the container and operating in opposition to the valve on the plunger, and a restricted vent connecting a lower portion of the cylinder with a lower portion of the chamber.
6. Apparatus according to claim 1 provided with a foot valve disposed in a lower portion of the pump cylinder and connecting the latter with the container and having a movable member which acts in opposition to the valve on the plunger by opening as the plunger is raised, and a restricted vent in the member connecting the container with the lower portion of the cylinder.
7. Apparatus according to claim 1 in which the springing means is a coil spring disposed in the cylinder below the plunger and so proportioned that it is continuously under compression.
8. Apparatus according to claim 1 in which the springing means is a coil spring describing the frustum of a cone and disposed in the cylinder below the plunger.
9. Apparatus according to claim 1 in which the springing means is a coil spring describing the frustum of a cone and disposed in the cylinder below the plunger with its big end down.
10. In apparatus of the class described, the combination which comprises a container for liquid, a pump having a cylinder projecting downwardly into the container, a tubular plunger in the cylinder with an inlet from the cylinder, an

exterior conduit connected to the tubular plunger and having a discharge end that may be disposed below the level of liquid in the container, a venting means to atmosphere in an open portion of the cylinder, and springing means for holding the plunger inlet above the vent.

11. Apparatus according to claim 10 provided with a disk-type foot valve at the bottom of the cylinder, the disk of the valve being resilient and having a small orifice therein for ejecting a jet of fluid into the container.

12. Apparatus according to claim 10 in which the springing means is a helical coil wound in frusto-conical shape and disposed in the cylinder below the plunger.

13. Apparatus according to claim 10 provided with a ball-type check valve in the tubular plunger above the inlet, with a ball of resilient material that seats when the plunger is raised.

14. Apparatus according to claim 10 in which the venting means comprises an orifice in the cyl-

inder wall above the normal liquid level in the container, and a second orifice in the outside wall of the apparatus above that liquid level and out of line of the first orifice.

15. Apparatus according to claim 10 in which the springing means is a coil disposed in the cylinder along the axes thereof below the plunger and so proportioned that it is under compression even when the plunger inlet is above the venting means.
